COIN REJECTION SYSTEM

Spencer L. Childers, Fresno, and William B. Warren, Madera, Calif., assignors, by mesne assignments, to The Vendo Company, Kansas City, Mo., a corporation of Missouri

Application April 23, 1951, Serial No. 222,501

16 Claims. (Cl. 194—2)

The present invention relates to coin operated vending machines and more particularly to a coin rejection system therefor operable to return normally acceptable coins when for any of several reasons the vending machine with which the system is associated is rendered inoperable.

For purposes of descriptive convenience the subject invention is illustrated in connection with the coin changer comprising the subject matter of our copending United States patent application Serial No. 216,236, filed March 17, 1951 and now abandoned, with Thomas K. Algor as co-inventor, and the coin handling mechanism for coin changers and the like employed in the coin changer comprising the subject matter of our copending United States patent application Serial No. 222,502, filed April 23, 1951, now abandoned.

In the operation of vending machines, improper or irregular performance constitutes a primary source of customer dissatisfaction. Such malfunction is characterized by failure to deliver vendable merchandise upon receipt of a coin of appropriate triggering denomination, failure to signal depletion of available merchandise for vending purposes, failure to render appropriate change for accepted coins, failure to signal depletion of a supply of change making coins, jamming incident to delivery of merchandise to a delivery chute while the chute is still occupied by previously vended merchandise, jamming of coin changers employed therein because of faulty coin detection in a change coin accumulating reservoir, and like difficulties. Although these and other difficulties have received considerable attention, previous methods to provide solutions thereto have not been entirely successful. It is an object of the present invention to provide a coin rejecting system that is entirely mechanical in its operation which is fully effective in obviating the aforesaid difficulties.

It is the general practice in coin operated vending machines to employ coin changers in following relation to coin selectors designed to reject all spurious objects, coins of other than predetermined acceptable denominations, and damaged coins which might subject the coin changer to jamming. Such selectors commonly subject the coins to thickness measurements, diameter measurements, weight measurements, and tests of composition based upon resilience, electrical conductivity, response to magnetic fields and the like. There are many suitable selectors commercially available and the instant application makes no greater detailed reference to the structure thereof than to describe lock-out fingers as employable in blocking relation to the coin paths thereof.

Coin changers employed with selectors receive only pretested and accepted coins of predetermined denomination or denominations. When more than one denomination is received, the coins are fed from the selector to the changer in segregated condition in chutes individual to the denominations. Coin changers generally serve to lock a mechanism such as a vending machine in which

2

they are employed, against operation; to release the mechanism for operation upon receipt of a coin of a predetermined denomination; and similarly to release the mechanism upon receipt of a coin in excess of the predetermined denomination and render an appropriate amount of change therefor.

Although not limited to such specific operational environment, the system of the present invention is most fully effectively employed in conjunction with a coin selector and coin changer of the character described mounted in a vending machine having a merchandise containing magazine and a delivery chute into which the merchandise is discharged incident to the completion of the vending cycle involving successive use of the selector, changer and magazine.

Another object is to provide a lock-out system of the character described for excluding all coins when the magazine of an associated vending machine is depleted of its supply of vendable merchandise.

Another object is to provide a system of the character described in the preceding paragraph that concurrently signals the absence of vendable merchandise.

Another object is to provide a lock-out system operable to reject all coins when a delivery chute, compartment or the like of a vending machine with which it is associated is still occupied by previously vended merchandise.

Another object is to provide a lock-out system operable in connection with a coin changer adapted to detect availability of change making coins, to reject all coins for which there is an inadequate supply of change making coins, and to signal the denomination or denominations of coins for which adequate change can be made.

Other objects are to provide improved elements and arrangements thereof in a device of the character and for the purposes set forth that are entirely mechanical in operation, economical to produce, durable in structure and fully effective in accomplishing the intended functions.

Further objects and advantages will become apparent in the subsequent description in the specification.

Referring to the drawings:

Fig. 1 is a fragmentary front elevation of a vending machine for refrigerated bottled beverages having a portion thereof broken away to reveal relevant internal structure.

Fig. 2 is a fragmentary horizontal section of the vending machine taken on line 2—2 of Fig. 1.

Fig. 3 is an enlarged elevation of a coin changer and associated structure employed in the vending machine illustrating details of the lockout system of the present invention.

Fig. 4 is a fragmentary vertical section taken through a portion of the coin changer showing a coin tube employed therein and a coin detecting finger associated therewith.

Fig. 5 is an enlarged side elevation of the coin detecting finger.

Fig. 6 is a fragmentary section of the vending machine taken on line 6—6 of Fig. 1, which has been foreshortened for illustrative convenience.

Fig. 7 is a view somewhat similar to Fig. 6 demonstrating the detection of a vended bottle located in a vending chute and the reaction of the lockout system thereto.

Fig. 8 is a fragmentary section taken on line 8—8 of Fig. 1.

Fig. 9 is a section similar to Fig. 8 but showing structure thereof in an alternate operable position.

Fig. 10 is a fragmentary enlarged section taken on line 10—10 of Fig. 1.

Fig. 11 is a section taken on line 11—11 of Fig. 10.

Fig. 12 is a fragmentary elevation of the inside of a

door mounted on the vending machine showing a portion of the rejection system of the present invention mounted thereon.

Fig. 13 is a fragmentary section taken on line 13—13 of Fig. 1.

Referring in greater detail to the drawings:

In Figs. 1 and 2, a vending machine for refrigerated bottled beverages is indicated generally at 20 having an insulated cabinet 21 closed by an insulated door 22. The door has a compartment 23 formed therein for purposes of housing a coin selector 24 and a change-making mechanism 25. The selector may be of any appropriate form and is not described in detail herein inasmuch as several suitable forms are commercially available. Suffice it to observe that the selector is adapted to receive coins of various denominations in random order, to reject all spurious objects and coins of other than predetermined size and shape, and to segregate acceptable coins into respective denominations. For purposes of illustrative convenience, the change-making mechanism 25 employing the coin rejecting system of the present invention is illustrated in connection with a selector adapted to accept nickels, dimes and quarters and to segregate the same for delivery to the change-making mechanism along paths of travel 26, 27, and 28, respectively, shown in dotted lines in Fig. 3.

The compartment 23 is closed by a hingeably mounted door 30 having a coin-receiving slot 31 and a signaling window 32 formed therethrough. A bottle delivery chute 33 extends from within the cabinet 21 through the door 22 and compartment 23. The chute is conveniently closed by pivotally-mounted flap 34. An externally accessible change cup 35 is also provided in the door 30. For purposes of assembling convenience, an oblong opening 36 is also formed in the door 30.

In Fig. 2, a magazine 40 for bottled beverages 41 is mounted for rotation about a substantially erect axis by means not shown. The magazine may be of any suitable form, that illustrated being of the type shown and described in United States Patent No. 2,290,275 issued to Harry S. Childers on July 21, 1942. It will of course be understood that the magazine may take various other forms such as that shown in United States Patent 2,482,245 issued September 20, 1949 to Harry S. Childers relating to "Dispensing Apparatus," and United States patent application Serial No. 794,045, filed December 26, 1947 by Harry S. Childers, entitled "Coin Controlled Vending Machine," now Patent No. 2,610,100 issued September 9, 1952, and others.

As evident in Fig. 5, a mounting box 45 of sheet metal or the like is provided in the compartment 23 having a back 46 releasably mounted in the door 22, substantially erect side walls 47 and 48, and a bottom wall or floor 49. The mounting box shown is open at the top and to the front. A bearing plate 50 is mounted across the front of the box and secured to the side walls 47 and 48. The position of the bearing plate is best observed in dash lines in Fig. 3 and in full lines in Fig. 10.

A drive shaft 55 is rotatably mounted between the back wall 46 of the mounting box and the bearing plate 50 into the compartment 23 substantially centrally of the change-making mechanism 25, as most clearly shown in Fig. 10. The shaft 55 extends forwardly of the door 30 with a handle 61 secured thereto and extending radially therefrom externally of the door. The drive shaft has driving connection with the magazine 40 by any suitable means, several suitable forms being shown in the patents and patent applications to which reference has been made, including a toothed wheel 62 rotatably mounted on the shaft 55, whereby rotation of the drive shaft advances a bottle 41 to a vending position for release and descent into the delivery chute 33.

Coin drum

A substantially cylindrical coin drum 75 is secured

concentrically on the drive shaft 55 within the mounting box 45, as shown in Figs. 3 and 10. The coin drum may take several forms but preferably is of the structure comprising the subject matter of a United States patent application entitled "Coin Handling Mechanism for Coin Changers and the Like", concurrently filed herewith.

The drum provides a plurality of peripherally disposed coin compartments. As most clearly evident in Fig. 10, the drum provides a compartment 76 for nickels, a dime compartment 77, and a quarter compartment 78.

The compartments may be of sufficient depth to receive at least one coin of each compartment's respective denomination. The compartments are peripherally disposed for gravitational receipt of the coins and gravitational discharge thereof during rotation of the drum. For descriptive convenience, the nickels are indicated generally at 80. The compartments 76, 77, and 78 are of such size and shape that only the last of any number of coins which the compartments are adapted to receive extends radially from the drum so that the peripheral portions of the extended coin are available for coin changer triggering operation.

Funnel member

25 A funnel member 86 is mounted directly above the coin drum and is adapted to receive coins from their respective paths of travel through the selector 24 and to deliver such coins to their appropriate compartments in the drum in the edgewardsly disposed attitudes when the 30 compartments are upwardly disposed. The member 86 conveniently consists of a plurality of spaced plates 87 of the form shown in Fig. 10.

Shaft locking

35 As previously indicated, the toothed wheel 62 is rotatably mounted on the drive shaft 55. Inwardly of the back 46 of the mounting box 45, a ratchet wheel 90 is rigidly secured to the toothed wheel 62. The toothed wheel 62 and ratchet wheel 90 are of unitary construction or rigidly interconnected for unitary rotational movement. A 40 pawl 91 is pivotally mounted on the back 46 for releasable engagement with the ratchet wheel and urged into such engagement by means of a compression spring 92 located between the pawl and a bracket 93 extended from the back, as shown in Fig. 3. An arcuate dwell 94 is formed in the coin drum 75 adjacent to the ratchet wheel 90 preferably traversing approximately 15° of the periphery of the drum. A boss 95 integral with the ratchet wheel 90 and toothed wheel 62, and eccentric thereto, is extended into the dwell 94. Shoulders on opposite ends of the dwell 94 limit travel of the drum 75 relative to the boss, ratchet wheel, and toothed wheel 62 to approximately 15°. Greater relative movement provides driving interconnection of the drum with the ratchet wheel and thus the drive shaft 55 by engagement of the boss and such a shoulder. The delayed driven interconnection permits coin detection, soon to be described, preliminary thereto. A locking pawl 96 is pivotally mounted concentrically of the ratchet pawl 91, as on a common journal 97 and extended for reciprocal movement to and from the path of travel of the boss. A spring 98 urges the locking pawl into the path of travel of the boss.

Coin detection and shaft release

65 A plurality of detecting levers 100 are pivotally mounted concentrically of the pawls 91 and 96 on the journal 97 for movement toward and from the drum. A detecting lever is provided in alignment with each of the compartments 76, 77, and 78 and has a contact end extended into the path of travel of its respective compartment's coin upon drum rotation in a clockwise direction, as viewed in Fig. 3. To urge the detecting levers into positions with their contact ends disposed in the paths of travel of the coins, a bracket 101 is extended from the locking pawl transversely of said levers. Conversely, movement of a

contact end of any of the detecting levers away from the drum through bracket engagement moves the locking pawl 96 out of the path of travel of the boss 95. It will be apparent that with no coins in the compartments of the coin drum 75, rotation of the operating handle 61, in a clockwise direction as viewed in Fig. 1, will bring the boss 95 into engagement with the locking pawl 96 and preclude rotational movement beyond the approximate 15° permitted by the dwell 94. When the handle is released its weight causes it to gravitate into the horizontal position shown in Fig. 1 with the compartments 76, 77, and 78 upwardly disposed to receive appropriate coins from the funnel member 86. It will be recalled that the handle 61 may be rocked through approximately 15° of rotation without motivating the toothed wheel 62 because of the dwell 94. When the handle 61 is rotated in a clockwise direction as viewed in Fig. 1 with a coin edgewards extended from the periphery of the drum 75, the edge of the coin passes under the adjacent end of that coin's respective detecting lever 100 and raises the same. Upward movement of the coin detecting lever in engagement with the bracket 101 lifts the locking pawl 96 from boss engagement against the urging of the compression spring 98. This releases the ratchet wheel 90 and thus the drive shaft 55 for continued rotation and permits motivation of the magazine 40 through its drive linkage to bring a bottle 41 or other unit of vendable merchandise to a vending position for release and descent into the chute 33.

Change supply

As shown in Figs. 3 and 10, a coin tube or reservoir 105 is mounted in a substantially erect attitude in vertical alignment with the coin drum 75. The tube is of such diameter to receive in stacked relation coins of the smallest denomination accepted by the drum for change making purposes. In the arrangement described, the tube is adapted to receive nickels from the coin drum through an open upper end thereof. A dime change slide 106 and a quarter change slide 107 are mounted for independent reciprocal movement in a channel member 108 mounted on the floor 49 of the mounting box. The change slides provide juxtapositionable pockets vertically aligned with the coin tube. Obviously any desired number of slides having pockets adapted to receive any predetermined number of coins may be employed. In the illustrative construction, the dime slide provides a pocket adapted to receive a single nickel, as shown in Fig. 4. The quarter slide provides a pocket adapted to receive three nickels so that if both the dime slide and the quarter slide are concurrently moved a total of four nickels will be withdrawn from the bottom of the coin tube for change making purposes. The floor 49 of the mounting box 45 also constitutes a floor under the pockets in the coin slides and is apertured, as at 109. When the slide is moved to the right, as viewed in Fig. 3, it carries with it the coin or coins in its pocket and deposits the same through the aperture 109 for descent through a coin chute 110 mounted in registration therewith, shown in Fig. 6 into the change cup 35.

In order to direct dimes, quarters, and nickels when the coin tube 105 is full to a coin accumulating bank, not shown, a coin directing member 115 is mounted on the back 46 of the mounting box 45 below the coin drum 75. As shown in Fig. 10, the coin directing member provides a quarter channel 116, a dime channel 117 and a nickel channel 118 defined by walls 119 upwardly extended from the member. As evident in Fig. 3, the bottoms of the channels have arcuate portions concentric to the coin drum extending from a position laterally adjacent to the drum in the direction of drum rotation from the top thereof to a position below the drum and thence downwardly and to the left as viewed. The bottoms of the channels are spaced from the drum sufficiently lightly to engage the peripheries of their respective coins carried by the compartments 76, 77 and 78 upon drum rotation while

such coins are nested within their respective compartments. This spacing has been found to impart a rolling action to the coins and to assure their dependable conveyance out the lower end of the directing member. The nickel channel is slotted directly above the coin tube for gravitational descent of nickels therethrough into the tube. The spacing of the coin directing member 115 above the floor 49 is such that when the coin tube 105 has a predetermined reserve of change making nickels therein subsequent nickels rolled along the nickel channel 118 roll over the top of the stacked nickels in the tube and out the lower end of the directing member. For purposes of convenient manual loading of the coin tube preliminary to operation of the described apparatus, a slot 120 is provided in the coin tube near the upper end thereof.

It is preferable to provide a box or other convenient container not shown, below the floor 49 and to provide an opening 121 through the floor in registration with the box or container, not shown, which serves as a coin accumulating bank. A slide member 122 extends downwardly from the lower end of the coin directing member to the opening 121.

Change slide manipulation

25 The change slides 106 and 107 are moved either together or the dime slide 106 alone to deposit a nickel or nickels for change by means herein shown but not specifically described. Suffice it to state that a stud 135 axially extended from the drum 75 coacts with either of a pair of fingers 136 or 139 to actuate the slides.

Lockout system

Not only is it desirable to return coins inserted during rotation of the coin drum 75 and coins inserted after such a coin's respective compartment in the coin drum is full, as previously described, but it is also important to preclude rotation of the drive shaft 55 and to reject all coins when there is a bottle in the delivery chute 33 not yet removed by the customer. The vending of an additional bottle when the chute is already occupied is conducive to bottle breakage and jamming of the vending machine. In addition, it is also desirable to preclude rotation of the drive shaft 55 and to reject all coins when the magazine 40 does not contain a bottle in position to be vended in response to a succeeding step of rotation of the magazine. Still further, it is desirable to reject all dimes and quarters when there is an insufficient quantity of change making coins available in the coin tube 105. To these ends a lockout system is provided in combination with the coin changer which is described at this point.

As shown in Figs. 3, 8 and 9, a pair of hinge brackets 165 are mounted on the back 46 rearwardly of the selector 24. A nickel lockout lever 166 is pendently mounted in one of the brackets 165 by a horizontal pintle 167 and is movable to and from the selector. The lockout lever 166 is provided with a rearwardly curved cam 168, a laterally extended arm 169, and a horizontal lockout finger 170 extendible into the coin path 26 for nickels upon forward pivotal movement and retracted from the coin path when suspended freely on the pintle 167.

A dime and quarter lockout lever 175 is pendently mounted in the other bracket 165 on a pintle 176. The pintle 176 is preferably spaced from the back 46 a distance slightly greater than the spacing of the pintle 167 therefrom for pendent support of the dime and quarter finger outwardly adjacent to the arm 169 of the nickel lever 166. The dime and quarter lever provides an arcuate rearwardly directed cam 177, a horizontal dime lockout finger 178 extendible into the path of travel 27 of dimes passing through the selector 25, and a horizontal quarter lockout finger 179 extendible into the path of travel 28 of quarters descending through the selector. Forward pivotal movement of the dime and

quarter lockout lever 175 moves the horizontal fingers 178 and 179 into the dime and quarter paths while free suspension of the finger on the pintle 176 causes the horizontal portions to assume positions removed from the selector.

To divert all coins when a bottle is in the chute 33 and thus to continue locking association of the boss 95 and locking pawl 96, the flap 34 is provided with an extension 182, as shown in Figs. 6 and 7. A bar 183 having elongated longitudinal openings 184 formed therein is slidably mounted in an erect position against the back 46, as by headed bolts 185 passed through the openings and secured to the back. The lower end of the bar 183 provides a shoe 186, shown in Figs. 6 and 7 adapted to rest on the extension 182 whereby assumption of a closed position by the flap 34 elevates the bar and pivotal movement of the flap outwardly, as caused by a bottle descending in the chute 33, permits gravitational descent of the bar. For more dependable guiding of the shoe, a guide sleeve 187 is mounted in the door 22 in circumscribed relation to the bar. The upper end of the bar is forwardly directed as at 188 in a position engageable with the cam 168 of the nickel lockout lever 166 when the bar is in its lowermost position, and disengaged therefrom when the bar is elevated by the flap 34 moving to closed position.

It will be seen that downward movement of the bar 183 causes the forwardly directed portion 188 thereof to ride against the cam 168 and to force the nickel lockout lever 166 and finger 170 forwardly, blocking the coin path 26. Such forward movement brings the arm 169 into engagement with the dime and quarter lockout lever 175 and concurrently blocks the paths 27 and 28. In such condition, all coins normally directed to the funnel member 86 are deflected from their normal paths and by means of an inclined plate 189 are directed into a chute 190 leading to the rejection tube 132. The plate 189 is normally a portion of the selector and is shown in dotted line in Fig. 3.

As shown in Figs. 2 and 13, an arm 195 is pivotally mounted on a floor 196 of the cabinet 21 in a position below the magazine 40 and in radial relation thereto. A blade 197 is mounted on the arm in a position engageable with a bottle 41 immediately in advance of the vending position, indicated generally at 198, aligned with the chute 33. A spring 199 urges the arm and thus the blade upwardly for bottle engagement. A second arm 205 is mounted for pivotal movement in a substantially horizontal attitude, as at 206, in facing relation to the door 22 and appreciably below the blade 197. A rod 207 pivotally interconnects the arm 195 and the arm 205 for corresponding pivotal movement, the former in vertical travel and the latter in horizontal travel.

As shown in Figs. 1, 2, 12 and 13, a rod 209 is rotatably mounted in an erect position on the inside of the door 22 so as to have a lower end portion adjacent to the arm 205 when the door is closed. A finger 210 is horizontally extended from the rod 209 for engagement with the arm 205 when the door is closed. A signal shaft 211 is rotatably mounted in a substantially horizontal position in the mounting box 45 adjacent to the levers 166 and 175 rearwardly of the selector 24. An arm 212 is radially extended from the shaft 211 inwardly of the door 22. A corresponding arm 213 is radially extended from the rod 219. A rigid member 214 pivotally interconnects the arms 212 and 213 so that the shaft 211 is rotatably positioned in response to the elevational movement of the blade 197 in its detection of bottles immediately in advance of the vending position 198.

In Fig. 3 a pair of arms 218 and 219 are shown extended from the signal shaft 211. The arm 218 has a forwardly extended cam-shaped portion 220 engageable with the arm 169 of the nickel lockout lever 166. As the shaft is rotated in a counterclockwise direction, as

viewed in Fig. 3, incident to upward movement of the blade 197 indicative of an empty magazine 40, the cam-shaped portion 220 forces the arm 169, the nickel lockout finger 170, and the dime and quarter lockout fingers 178 and 179 into blocking relation to the coin paths 26, 27 and 28. The function of the arm 219 will subsequently be described.

In Figs. 3 and 4, a bifurcated bracket 225 is shown mounted on the channel member 108 adjacent to the coin tube 105 which is vertically slotted adjacent thereto. A detection plate or finger 226 is pivotally mounted in the bracket 225 for reciprocal movement between a rest position extended into the coin tube and a position retracted therefrom. A detection rod 227 is mounted, as at 228, on the back 46 of the mounting box 45 and provides a lower end 229 outwardly extended through an elongated slot 230 formed in the detection plate. The detection rod is limited to elevational movement only by its mounting on the back 46. As illustrated in Fig. 5, 20 the detection plate 226 is formed with a lower arcuate edge 231 eccentric of the pivot. The eccentricity is such that the portion of the arcuate edge nearest the coin tube when the plate is retracted from the tube, is radially extended from the pivot point of the detection plate further than any other portion of the edge. This prevents jamming of the detection finger against a partial stack of coins in the coin tube during movement into the tube. No jamming can occur during retractive movement because no coins can be added to the tube while the plate is extended therein.

A cam 235 disposed between the ratchet wheel 90 and the coin drum 75 and having a flat 236 disposed in alignment with the compartments 76, 77 and 78 axially of the shaft 55 is formed on the ratchet wheel 90, as evident in Fig. 11. The detection rod 227 provides a horizontal portion 237 rested on the flat 236, and a horizontal portion 238 engageable with the cam 177 on the finger 175. The detection rod is upwardly extended from the horizontal portion 238 and provides longitudinally adjustable portions interconnected by a coupling 239 having left and right hand screwthreaded engagement with adjacent portions of the rod whereby the length thereof may conveniently be adjusted for purposes soon to become apparent.

It will be clear that upon rotation of the drum 75 the detection rod 227 is elevated pivotally retracting the detection plate 226 from the coin tube 105 for the convenient reception of nickels therein. Upon completion of rotation of the drum, the rod is permitted to descend by the flat 236, permitting the detection plate 226 to re-enter the coin tube unless blocked by nickels therein. The detection plate is positioned at such an elevation relative to the coin tube that inward pivotal movement thereof is blocked by nickels whenever there is a supply adequate for filling the pockets in the slides 106 and 107. If upon completion of drum rotation, the plate pivots inwardly of the coin tube, the detection rod 227 gravitationally descends because of the flat 236, and through engagement of the horizontal portion 238 with the cam 177 moves the dime and quarter lockout fingers into blocking relation with the dime and quarter paths 27 and 28.

As a customer courtesy, signs are movably mounted behind the signaling window 32, as indicated in Figs. 3, 8 and 9. A transversely arcuate coin sign 245 bearing the indicia "5¢ only" and "5¢, 10¢ or 25¢" longitudinally thereof is pivotally mounted by a plate 246 on the back 46 concentrically of the sign for movement between positions selectively displaying the legends. The length of the detection rod 227 is adjusted by means of the coupling 239 so that the upper end of the rod abuts the plate 246 and so that when the detection plate 226 is pivoted inwardly of the coin tube 105, indicating an inadequate supply of change-making nickels, the sign 245 gravitates downwardly so that the legend "5¢ only" is visible through

the window 32. When the detection rod 227 is held in its uppermost position by nickels in the coin tube blocking the detection plate 226, the sign is held upwardly, in the position shown in Figs. 3 and 8 so that the legend "5¢, 10¢ or 25¢" is visible through the window.

A transversely arcuate merchandise sign 248 displaying "empty" thereon, is pivotally mounted by bracket arms 249 outwardly concentric to the coin sign 245. A pair of vertically aligned elongated openings 250 are formed through the side wall 48 adjacent and below the pivotal mounting of the merchandise sign 248. An elongated slide member 251 is mounted for reciprocal elevational movement on the side wall 48 by pins 252 mounted thereon, extended through the openings 250 and provided with heads 253 outwardly of the wall. The upper end of the slide member is pivotally connected to one of the bracket arms 249 by a pivot pin 254. The lower end of the slide member is outwardly turned, as at 255, for rested support on the arm 219 mounted on the signal shaft 211. When the shaft and arms 218 and 219 are in normal operating position, as shown in Figs. 3 and 8, the dime and quarter lockout fingers 178 and 179 are retracted from the coin paths 27 and 28 and the merchandise sign 248 gravitationally positioned below the window 32 where it is not visible from externally of the vending machine. When the shaft 211 is rotated in a counterclockwise direction as viewed in Fig. 3, indicative of an inadequate supply of bottled beverages 41 in the magazine 40, not only are the dime and quarter paths 27 and 28 blocked by the lockout fingers 178 and 179 but the arm 219 elevates the slide member 251 and moves the merchandise sign 248 upwardly into a position in covering relation to the coin sign 245 externally visible through the window 32 and displaying the word "empty."

Operation

The operation of the coin changer of the present invention is believed to be clearly apparent and is briefly summarized at this point. When a nickel, dime, or quarter is received in an edgewise disposed position in the coin drum 75 and the handle 61 rotated in a clockwise direction, as viewed in Figs. 1 and 3, such a coin passes under the extended end of its respective detecting lever 100 pivoting the lever so that through engagement with the bracket member 101 the locking pawl 96 is removed from the path of travel of the boss 95. Pivotal movement of either of the detecting levers 100 aligned with the dime and quarter compartments pivots its respective change-making finger 136 or 139 so as to dispose the upper end thereof in the path of travel of the stud 135.

Continued rotation of the coin drum causes the stud 135 to snag the upwardly extended end of any change-making finger 136 or 139 in the path of travel thereof and the stud pivots the finger in a counterclockwise direction, as viewed in Fig. 3, so that such finger's respective slide 106 or both 106 and 107, are moved to deposit the coins contained in the pockets thereof through the aperture 109.

The dime slide 106 is moved in response to rotation of the drum with a dime in the dime compartment 77 and a single nickel is dropped through the aperture 109 and descends into the change cup 35. When a quarter is inserted into the drum rotation thereof causes pivotal movement of both the change making fingers 136 and 139 and both the dime slide 106 and quarter slide 107 are moved over the aperture 109 and a total of four nickels dropped therethrough into the change cup 35.

The coin rejecting or lockout system of the present invention is entirely mechanical in its operation and believed to be appreciably more dependable than known systems of the same general purpose. Being mechanical, sources of maladjustment tending to render the system inoperable are minimized, and obvious economies in production effected. All coins for which change is required are re-

jected by the system whenever an inadequate supply of change-making coins is contained by the tube 105 and concurrently therewith a signal is provided for the customer's convenience indicating that the coin changer with which the system is employed can only accept coins for which no change is required. When a unit of vendible merchandise is permitted to remain in delivered position, the system precludes vending of additional articles. This effectively minimizes jamming, breakage, and the like.

10 The system accurately detects the presence of vendible merchandise in a position to be dispensed upon a successive vending operation and renders the associated vending machine inoperable when the supply of vendible merchandise is depleted. Not only does the system reject all coins when there is no merchandise available for vending purposes but concurrently therewith signals customers that the associated vending machine is "empty."

The system is simple in structure, of far greater durability than the mechanisms with which it is normally associated, requires an absolute minimum of servicing, and completely obviates all of the difficulties incident to the employment of electrical detection of vendible merchandise encountered in conventional systems.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and systems.

Having described our invention, what we claim as new and desire to secure by Letters Patent is:

1. In a vending machine having a merchandise magazine and a coin operating mechanism having a plurality of coin pathways therethrough, the combination of a coin tube adapted to receive coins from one of the pathways, a first lockout member mounted adjacent to the pathway from which the coin tube is adapted to receive coins, a second lockout member mounted adjacent to the other pathway for movement to and from the same, the first lockout member having a portion thereof disposed for engagement with the second lockout member at the side thereof opposite to its respective pathway, a blade mounted adjacent to the merchandise magazine for movement to and from the magazine, resilient means operatively associated with the blade urging the blade into the magazine, a detector finger, means mounting the detector finger adjacent to the coin tube for movement between a rest position in the tube and a position retracted from the tube and so that the finger is urged into the rest position, a shaft rotatably mounted adjacent to the portion of the first lockout member engageable with the second lockout member, a control arm extended from the shaft having a cam engagable with said portion of the first lockout member upon shaft rotation to urge the first lockout member into its respective pathway and by engagement of said portion of the first lockout member with the second lockout member to urge said second lockout member into its pathway, a mechanical linkage interconnecting the blade and the shaft rotating the shaft to move the control arm into engagement with said portion of the first lockout member in response to movement of the blade into the magazine, and a detection rod connected to the detector finger of the coin tube for moving said second lockout member into its pathway in response to movement of the finger into the coin tube.
2. In a coin operated vending machine having a plurality of coin pathways therein, a coin tube for change-making coins mounted below one of the pathways and adapted to receive coins therefrom, a merchandise delivery compartment, and a magazine for vendible merchandise; the combination of a lockout member pendently mounted adjacent to the pathway from which the coin tube receives coins for pivotal movement to and from the pathway; a second lockout member pendently mounted adjacent to

the other pathways for pivotal movement concurrently to and from all of the pathways except that from which the coin tube receives coins, the first lockout member having a portion extended across the second lockout member on the side thereof opposite from the pathways whereby pivotal movement of the first lockout member into its pathway carries the second lockout member into its respective pathways; a finger mounted for pivotal movement to and from the coin tube eccentrically of its center of balance whereby the finger is urged into the coin tube; a detection rod connected to the finger and engagable with the second lockout member for pivoting said second lockout member into its respective pathways in response to pivotal movement of the finger into the coin tube; a blade pivotally mounted adjacent to the magazine for movement to and from the magazine; a spring engaged with the blade urging the blade into the magazine; means interconnecting the blade and the first lockout member and urging said member into its pathway in response to movement of the blade into the magazine, the first lockout finger carrying the second lockout member into its pathways by engagement therewith; a door pivotally mounted in the delivery compartment for engagement by merchandise therein; and a bar gravitationally rested on the door and lowered by the door in response to merchandise engagement, said bar having an end adjacent to the first lockout member and the first lockout member having a cam shaped portion engaged with the adjacent end of the bar whereby elevational movement of the bar pivots the first lockout member and the second lockout member therewith into their respective coin pathways.

3. In a coin operated vending machine having a coin changer including a rotatable drum having a plurality of coin pockets therein, a coin tube mounted below the coin drum, means for directing coins from one of the pockets of the drum into the tube upon drum rotation, and coin pathways above the drum individually aligned with the pockets therein; a lockout system comprising a lockout member pivotally mounted in pendent relation adjacent to the pathways having fingers extended for corresponding reciprocal movement to and from all of the pathways other than that aligned with the pocket from which coins are directed into the coin tube, said lockout member having a cam portion downwardly extended therefrom and oppositely from the pathways; a coin detection finger pivotally mounted on a horizontal axis adjacent to the coin tube for reciprocal movement to and from the tube; and a detection rod pivotally connected to the detection finger at a position opposite to the pivotal axis of the finger from the tube and upwardly extended therefrom, said detection rod having a substantially horizontal portion transversely extended above the drum and a second horizontal portion transversely extended in elevationaly adjacent relation to the cam portion of the lockout member at the side of the cam portion opposite to the pathways, the coin drum having a substantially cylindrical periphery and being provided with a flat thereon engageable with the first horizontal portion of the detection rod whereby the detection rod is elevated upon drum rotation to retract the detection finger from the tube and lowered for pivotal movement of the finger into the tube in response to engagement of said first horizontal portion of the detection rod with the flat on the drum, said second horizontal portion of the detection rod engaging the cam portion of the lockout member when the detection finger moves into the tube.

4. In a coin operated vending machine having a magazine for vendible merchandise, a vending chute into which vended merchandise is discharged from the magazine, a plurality of coin paths defined in the machine for coins of denominations individual thereto, and a coin tube mounted below the path for coins of the lowest denomination adapted to receive coins therefrom; a lockout system comprising a lockout finger mounted for reciprocal movement to and from each of the coin paths, said

75 fingers being gravitationally urged from their respective paths, the lockout fingers for all coin paths other than that of the lowest denomination being interconnected for unitary reciprocal movement, and the lockout finger of the lowest denomination having a control portion extended across the other fingers at the side thereof opposite to their respective coin paths and having a chute cam portion extended downwardly and away from the paths, the lockout fingers for the coin paths other than that of the lowest denomination having a cam portion integral therewith extended downwardly and away from the paths; a door pivotally mounted in the vending chute; a bar mounted for reciprocal elevational movement having a lower end gravitationally supported on the door and an upper end disposed for engagement with the chute cam portion of the lockout finger for the path of the lowest denomination; a detection member pivotally mounted adjacent to the magazine for reciprocal movement to and from a position in the magazine; resilient means engaged with the detection member urging the member into the magazine; a shaft rotatably mounted adjacent to the control portion of the lockout finger for the path of coins of the lowest denomination; a cam arm mounted on the shaft engageable with the control portion of said lockout finger; a mechanical linkage interconnecting the detection member and the shaft for translating pivotal movement of the detection member into the magazine into rotational movement of the shaft to bring the cam arm into engagement with said control portion of the lockout finger of said path for coins of the lowest denomination to urge said finger into its path; a coin detection member pivotally mounted adjacent to the coin tube for reciprocal movement to and from a position in the tube; and a detection rod mounted for reciprocal elevational movement

30 35 40 45 50 55 60 65 70

35 40 45 50 55 60 65 70

5 in the machine having a lower end pivotally connected eccentrically to the coin detection member and a portion thereabove engageable with the cam portion of the lockout fingers of the coin paths other than that of the lowest denomination.

5. In a coin operated vending machine having a cabinet, a magazine for vendible articles, a delivery chute below the magazine, a door pivotally mounted in closing relation to the cabinet, a coin changer mounted in the door including a rotatable drum having a plurality of coin pockets therein, a coin tube mounted below the coin drum, coin pathways defined in the door above the drum individually aligned with the pockets therein, and means for directing coins from one of the pockets of the drum into the tube upon drum rotation; a lockout system comprising a lockout finger pivotally mounted in pendent relation adjacent to each of the pathways and gravitationally urged from its respective pathway, the lockout fingers for all coin paths other than that aligned with the pocket adapted to supply coins to the coin tube being interconnected for unitary pivotal movement, the interconnected lockout fingers having a coin tube cam integral therewith and the lockout finger for the path aligned with the pocket adapted to supply coins to the coin tube having a chute cam and an arm extended therefrom transversely of the other fingers for movement of the other fingers into their respective pathways in response to movement of the finger having the chute cam into its pathway; a coin detection finger pivotally mounted on a horizontal axis adjacent to the coin tube for reciprocal movement to and from the tube; a detection rod pivotally connected to the detection finger at a position opposite to the pivotal axis of the finger from the tube and upwardly extended therefrom, said detection rod having a substantially horizontal portion transversely extended above the drum and a second horizontal portion transversely extended in elevationaly adjacent relation to the coin tube cam at the side of said cam opposite to the pathways, the coin drum having a substantially cylindrical periphery and being provided with a flat thereon engageable with the first horizontal portion of the detection rod whereby the de-

tection rod is elevated upon drum rotation to retract the detection finger from the tube and lowered for pivotal movement of the finger into the tube in response to engagement of said first horizontal portion of the detection rod with the flat on the drum; a substantially horizontal shaft mounted above the chute; a door pivotally mounted on the shaft having a lower portion pendently supported in the chute and an upwardly extended portion; an elongated bar having a lower end portion rested on the upper end portion of the door and an upper end adjacent to the lockout fingers angularly extended toward the fingers upwardly adjacent to the chute cam; means mounting the bar for reciprocal elevation movement; a detection member pivotally mounted in the cabinet on a substantially horizontal axis adjacent to the magazine and to the cabinet door for reciprocal movement to and from a position in the magazine; a compression spring mounted below the detection member and in engagement therewith urging the detection member pivotally into the magazine; an arm pivotally mounted about a substantially vertical axis adjacent to the cabinet door and below the detection member; a rod swivelly interconnecting the arm and the detection member for corresponding pivotal movement; a second rod rotatably mounted on the cabinet door in a substantially erect position; a finger transversely extended from the second rod in engagement with the arm whereby pivotal movement of the arm correspondingly rotates the second rod; a shaft rotatably mounted in the cabinet door in a substantially horizontal position adjacent to the arm of the lockout finger of the pathway aligned with the pocket adapted to supply coins to the coin tube; a cam arm transversely extended from the shaft adjacent to the lockout finger of the pathway aligned with the pocket adapted to supply coins to the coin tube and at the opposite side of said finger from its respective pathway engageable with the arm of said finger upon shaft rotation; a control arm transversely extended from the shaft; a second control arm transversely extended from the second rod; and a push-pull member pivotally interconnecting the extended ends of the control arms.

6. In a coin operated machine having a magazine for vendible merchandise, a vending chute into which vended merchandise is discharged from the magazine, a plurality of coin paths in the machine for coins of denominations individual thereto, and a coin tube mounted below the path for coins of the lowest denomination adapted to receive coins from said path; a lockout system comprising a lockout finger pendently mounted adjacent to each of the coin paths, the lockout finger of the coin path of the lowest denomination having means thereon engageable with the other fingers whereby movement of said lockout finger into its respective path carries the lockout fingers of the paths of the other denominations into their respective paths; a flap pivotally mounted in the vending chute; a bar member interconnecting the flap and the lockout finger of the path of the lowest denomination for corresponding pivotal movement; detection means mounted for pivotal movement to and from the coin tube at a position blocked by coins in the tube; a linkage interconnecting the detection means and the lockout fingers for the coin paths other than that for the lowest denomination and moving said fingers into their respective coin paths in response to movement of the detection means into the coin tube; a detection blade mounted for reciprocal movement to and from the magazine at a position occupied by vendible merchandise when the magazine is loaded; and a linkage interconnecting the detection blade and the lockout finger of the path of the lowest denomination and moving said lockout finger into its respective coin path in response to movement of the detection blade into the magazine.

7. In a coin operated vending machine having a magazine for vendible merchandise, a vending chute into which vended merchandise is discharged from the magazine, a

plurality of coin paths in the machine for coins of denominations individual thereto, and a coin tube mounted below the path for coins of the lowest denomination adapted to receive coins therefrom; the combination of 5 a lockout finger mounted for reciprocal movement to and from each of the coin paths, the lockout fingers for all coin paths other than that of the lowest denomination being interconnected for unitary reciprocal movement and the lockout finger for the coin path of the lowest 10 denomination being operatively associated with the other fingers for movement of all of said other fingers into their respective coin paths in response to movement of said finger of the path of lowest denomination into its path; detecting means mounted in the vending chute of 15 the vending machine engageable by merchandise therein; a linkage interconnecting the detecting means of the chute and the lockout finger of the lowest denomination for moving said finger into its respective path in response to the presence of merchandise in the chute; a detecting 20 blade mounted in the magazine of the vending machine for engagement with merchandise next to be vended from the machine; a linkage interconnecting the merchandise detecting blade and the lockout finger of the lowest denomination for moving said lockout finger into 25 its respective coin path when the magazine is empty; a coin detecting member mounted for pivotal movement to and from the coin tube and having a rest position in the tube; and a linkage interconnecting the coin detecting member and all of the lockout fingers other than that of 30 the lowest denomination and moving said fingers into their respective coin paths in response to movement of the coin detecting member into the tube.

8. In a vending machine having a magazine for vendible merchandise, a vending chute into which vended 35 merchandise is discharged from the magazine, a plurality of coin paths in the machine for coins of denominations individual thereto, and a coin tube mounted below the path for coins of the lowest denomination adapted to receive coins therefrom; the combination of a lockout 40 finger mounted for reciprocal movement to and from each of the coin paths, said fingers being gravitationally urged from their respective paths, the lockout fingers for all coin paths other than that of the lowest denomination being interconnected for unitary pivotal movement and the lockout finger of the coin path for the lowest denomination being operatively associated with the other lockout fingers for movement of said other fingers into their respective coin paths in response to movement of said finger of the lowest denomination into its respective 45 coin path; a flap pivotally mounted in the vending chute, a linkage interconnecting the flap and the lockout finger of the coin path of the lowest denomination for moving said finger into its respective coin path in response to engagement of the flap with merchandise in the chute; a 50 detection finger mounted for pivotal movement to and from a position occupied by merchandise in the magazine next to be vended from the machine; means resiliently urging the detection finger into said position; a linkage interconnecting the merchandise detection finger and the lockout finger of the coin path for the lowest denomination for moving said lockout finger into its respective coin path in response to movement of the detection finger into the position occupied by merchandise next to be vended from the machine; a coin detection member 55 mounted for pivotal movement to and from the coin tube and gravitationally urged into the tube at a position blocked by coins contained in the tube; a cam mounted in the machine rotated upon actuation of the machine for vending purposes; and a detection rod pivotally connected to the coin detection member and controllably positioned by the cam for retraction of the detection member from the tube during actuation of the machine and gravitational return to the tube upon completion of said actuation, said detection rod being operatively associated with all of the lockout fingers other than that of 60 70 75

the lowest denomination for moving said fingers into their respective coin paths in response to movement of the detection member into the coin tube.

9. In a vending machine having a magazine for vendible merchandise, a vending chute into which vended merchandise is discharged from the magazine, a plurality of coin paths in the machine for coins of predetermined denominations individual thereto, and a coin tube mounted below one of the paths adapted to receive coins therefrom; a lockout system comprising a lockout finger mounted in pendent relation adjacent to each of the coin paths for pivotal movement to and from its respective coin path, the lockout fingers for all coin paths other than that from which the tube receives coins being interconnected for unitary movement to and from their respective coin paths, a portion of the lockout finger of the path from which the tube receives coins being extended across the other lockout fingers at the side thereof opposite from said other lockout fingers' respective coin paths whereby movement of said finger into its respective path moves all of the other fingers into their respective paths; a flap pivotally mounted in the vending chute for engagement by merchandise discharged into the chute by the magazine, for upward pivotal movement in response to such engagement; a linkage interconnecting the flap and the lockout finger of the path from which the tube receives coins for urging the finger into its respective coin path in response to upward pivotal movement of the flap and by engagement of the extended portion of said finger with the other lockout fingers urging said other fingers into their respective coin paths; a detection blade pivotally mounted adjacent to the magazine for pivotal movement to and from a position in the magazine blocked by vendible merchandise when the magazine is loaded; resilient means urging the detection blade into the magazine; a linkage interconnecting the detection blade and the lockout finger of the path from which the tube receives coins for movement of said lockout finger into its respective path and the other lockout fingers into their respective paths in response to pivotal movement of the detection blade into the magazine; a coin detection member pivotally mounted adjacent to the coin tube for reciprocal movement to and from the tube, at a position at which the tube is adapted to contain coins, and said member being gravitationally urged into the tube; a cam mounted for rotation in the machine upon actuation of the machine for vending purposes; and a detector rod pivotally connected to the coin detection member and being together therewith controlled by the cam for elevation of the rod and retraction of the coin detection member from the tube during rotation of the cam and for gravitational descent of the rod and of the detection member into the tube upon completion of a cycle of cam rotation; the detector rod being operatively associated with all of the lockout fingers other than that of the path from which the tube receives coins for moving said fingers into their respective coin paths in response to movement of the coin detection member into the coin tube.

10. The system as defined in claim 9, including a coin sign bearing a first legend identifying the denomination of the coin path from which the tube receives coins and a second legend identifying all denominations of coins acceptable by the machine; means mounting the sign in the machine for movement between a rest position in the machine displaying the second legend and an alternate position displaying the first legend; an extension of the detector rod connected to the sign and moving the sign from rest position into said alternate position in response to movement of the coin detection member into the coin tube; a merchandise sign bearing a legend indicating absence of vendible merchandise in the magazine, mounted in the machine for movement between a rest position hidden in the machine and a displaying position in covering relation to the coin sign; and control means connected to the merchandise sign responsive to movement

of the detection blade into the magazine for moving the merchandise sign into display position.

11. The system as defined in claim 9 including a coin sign bearing a first legend identifying the denomination of the coin path from which the tube receives coins and a second legend identifying all denominations of coins acceptable by the machine; means mounting the sign in the machine for movement between a rest position in the machine displaying the second legend and an alternate position displaying the first legend; and an extension of the detector rod connected to the sign and moving the sign from rest position into said alternate position in response to movement of the coin detection member into the coin tube.
12. The system as defined in claim 9 including a merchandise sign bearing a legend indicating absence of vendible merchandise in the magazine, mounted in the machine for movement between a rest position hidden in the machine and a displaying position; and control means connected to the merchandise sign responsive to movement of the detection blade into the magazine for moving the merchandise sign into display position.
13. In a vending machine having a merchandise magazine and a coin operating mechanism having coin pathways therethrough, the combination of a coin tube adapted to receive coins from one of the pathways, a first lockout member mounted adjacent to the pathway from which the coin tube is adapted to receive coins, a second lockout member mounted adjacent to the other pathways, the lockout members having rest positions retracted from their respective pathways and coin blocking positions disposed within their respective pathways, the first lockout member having a portion thereof disposed for engagement with the second lockout member at the side thereof opposite to its respective pathway whereby movement of the first lockout member to coin blocking position moves the second lockout member to coin blocking position, a blade mounted adjacent to the merchandise magazine for movement to and from the magazine, said blade having a rest position retracted from the magazine and a detecting position extended into the magazine, a detector finger mounted adjacent to the coin tube for movement to and from the tube, said finger having a rest position within the tube and a position retracted therefrom, a first control linkage interconnecting the blade and the first lockout member for moving the first lockout member and thus the second lockout member to their coin blocking positions in response to movement of the blade into the magazine, and a second control linkage interconnecting the detector finger and the second lockout member for moving said second lockout member into its coin blocking position in response to movement of the detector finger into the coin tube.
14. In a coin operating vending machine having a coin changer including a rotatable drum having a plurality of coin pockets therein, a coin tube mounted below the coin drum, means for directing coins from one of the pockets of the drum into the tube upon drum rotation, and coin pathways above the drum individually aligned with the pockets therein; a lockout system comprising a lockout member mounted adjacent to the pathways having fingers correspondingly movable to and from all of the pathways other than that aligned with the pocket from which coins are directed into the coin tube; a coin detection finger pivotally mounted adjacent to the coin tube for reciprocal movement to and from the tube, the detection finger having a rest position within the tube and a retracted position removed from the tube; and a detection rod pivotally connected to the detection finger eccentrically of the pivotal axis of the finger and upwardly extended therefrom, said detection rod having a horizontal portion transversely extended above the drum and an upper end in controlling connection to the lockout member, the coin drum having a substantially cylindrical periphery and being provided

with a flat thereon engageable with the horizontal portion of the detection rod whereby the detection rod is elevated upon drum rotation to retract the detection finger from the tube and lowered for pivotal movement of the finger into the tube in response to engagement of the horizontal portion of the detection rod with the flat on the drum.

15. In a coin operated vending machine having a vending chute into which vended merchandise is dispensed upon actuation of the machine, a plurality of coin paths in the machine for coins of denominations individual thereto, and a coin tube mounted below the path for coins of the lowest denomination adapted to receive coins from said path; a lockout system comprising a lockout finger mounted adjacent to each of the coin paths for reciprocal movement to and from their respective paths, the lockout finger of the coin path of the lowest denomination having a portion extended across the other fingers at the side thereof opposite to their respective coin paths; a flap pivotally mounted in the vending chute; a bar member interconnecting the flap and the lockout finger of the path of the lowest denomination for corresponding pivotal movement; detection means mounted for pivotal movement to and from the coin tube at a position in predetermined space relation to the bottom of the tube; and a linkage interconnecting the detection means and the lockout fingers for the coin paths other than that of the lowest denomination and moving said fingers into their respective coin paths in response to movement of the detection means into the coin tube.

16. In a coin operated vending machine having a vending chute into which vended merchandise is dispensed upon actuation of the machine, a plurality of coin paths in the machine for coins of denominations individual thereto, and a coin tube mounted below the path for coins of the lowest denomination adapted to receive coins from said path; a lockout system comprising lockout members individually mounted adjacent to each of the coin paths for reciprocal movement to and from their respective paths, the lockout member of the coin path of the lowest denomination being operably associated with the other lockout members whereby movement of said lockout member of the coin path of the lowest denomination into its coin path moves the other lockout members into their respective coin paths and whereby said other lockout members can move into

their respective coin paths independently of the lockout member of the coin path of the lowest denomination; means mounted in the vending chute for reciprocal movement between a rest position in the chute engageable with merchandise disposed therein and a retracted position to which said means is displaced by merchandise dispensed into the chute; a linkage interconnecting the means mounted in the chute and the lockout member of the path of the lowest denomination moving said lockout member into its respective coin path in response to movement of the means mounted in the chute to retracted position; detection means mounted for pivotal movement to and from the coin tube at a position in predetermined spaced relation to the bottom of the tube; and a linkage interconnecting the detection means and the lockout members for the coin paths other than that of the lowest denomination and moving said members into their respective coin paths in response to movement of the detection means into the coin tube.
